IMAGE REPRODUCING APPARATUS

Warren H. Bliss, Orono, Maine, assignor to Radio Corporation of America, a corporation of Delaware

Application October 2, 1941, Serial No. 413,285

11 Claims. (Cl. 178—6.6)

The present invention relates to picture or image reproducing systems in general and is particularly applicable to facsimile systems wherein the picture signals are transmitted over radio channels. In some instances such transmissions, where occurring over relatively long distances particularly, are not entirely satisfactory due to unavoidable omissions of certain portions of the signals due, for example, to fading and the like.

The present invention has, therefore, as one of its principal objects that of providing a simple and conveniently used arrangement whereby many of the drop-outs or fill-ins occurring due to fading, static and the like are prevented. In this way, while the correction is in some respects of only a partial nature and does not entirely overcome all of the losses, there nevertheless is produced a better picture record or reproduction for the looker or user.

Broadly speaking, the present invention provides a system wherein for each scanning line of the picture, or any selected portion thereof, there is substituted for any drop-out or fill-in a reproduction of the preceding scanning line or a corresponding portion thereof. To accomplish this result the received signals are preferably caused to produce a pictorial record in substantially the usual manner, except that at time periods when the received signal strength falls below a predetermined average value the pictorial record will not be produced in the normal manner. However, with the invention, simultaneously with the production of the pictorial record provision is made for producing a non-pictorial record, which may be of several forms, such as a magnetic record or a record in the form of a latent image and somewhat resembling the sound recordings on a motion picture film but having no specific direct reference or likeness to the particular pictorial indication intended. After a predetermined time delay, as hereinafter to be explained in more detail, the non-pictorial record is converted into electrical energy. Then, by means of a switching arrangement activated under the control of the received signals the instrumentality to produce the pictorial record is controlled either directly by the received signals, after, of course, suitable amplification, or the means to produce the pictorial record is controlled by the signals resulting from the conversion of the non-pictorial record into electrical energy to the exclusion of a direct control from the signals instantaneously received.

It thus becomes an object and advantage of the present invention to provide a system of pic-

ture image and facsimile reception wherein improved types of records are produced.

Other objects are to provide a system for receiving facsimile messages wherein the objection to static, fading and the like as influencing the received signals is made less apparent in the finished record.

Other objects and advantages, as it will be apparent, will at once suggest themselves to those skilled in the art when the following specification is read in conjunction with the accompanying drawing, wherein the single figure thereof represents schematically one of a plurality of forms which the invention may assume.

In any form of picture transmitting or facsimile apparatus picture signals are transmitted from a sending point over a suitable communication channel so that values of light and shadow are portrayed as a sequence of signals for each line of the picture and each existing line of the picture is usually followed by a synchronizing signal, although this is not in some instances necessary. After signals representing a complete picture made up of any predetermined number of individual scanning lines have been transmitted these groups of signals are usually followed by a framing signal.

The transmission may be in accordance with many various forms, among which are the so-called constant frequency variable dot methods, as exemplified, for instance, by Alexanderson Re-issue Patent No. Re. 20,153, of November 3, 1936, and by the Shore and Whitaker Patent No. 2,083,245, of June 8, 1937, and further explained in Proceedings of the Institute of Radio Engineers, vol. 23, No. 12, for December, 1935, in an article entitled "Photoradio apparatus and operating technique improvements," by Callahan et al. Another method which has been successfully used is the so-called sub-carrier frequency modulation system, as was explained particularly by Messrs. Mathes et al. in "RCA Review" for October, 1939, in an article entitled "Radio facsimile by sub-carrier frequency modulation."

Generally speaking, the signals representing the varying light values and the synchronizing or control signals are transmitted to receiving points as modulations of a carrier frequency and such modulations may be amplitude, frequency and/or phase or a mixture of the above. In any such types of systems the transmitted signals representing the lights and shadows on the picture accompanied by the synchronizing signals are suitably received, amplified and detected, and then caused to control the operation of a re-

55

cording stylus or an equivalent instrument. The recording instrument is adapted to produce marking indicia upon a record sheet passed about a recording drum, which is usually rotated or in some instances reciprocated so that one rotation or one motion laterally represents one scanning line. The recording drum is driven from any suitable prime mover, such as a motor, which is maintained at a speed synchronous with the transmitter. Synchronism is usually maintained under the control of the received synchronizing and framing signals.

In the present invention the transmitted picture and synchronizing signals are duly received on a receiving antenna 1, or the signals may be received over a suitable wire line communication channel. After the signals received are duly amplified and detected in the receiver and amplifier unit 3, which is of a conventional design, they are then supplied to a line amplifier and converter unit 5, whose output is supplied in parallel to a switching instrument, represented within the dotted outline 7, to a switch control unit 9, represented within the dotted outline, and to a magnetic recorder 11, which is of any suitable and known type. The signal output from the switching device 7 is supplied to a facsimile recorder unit 15 which is conventionally represented and which is driven from any suitable form of prime mover such, for example, as the motor 17. The signals from the line amplifier and converter unit 5 are also applied to the switch control unit, which, in the manner hereinafter to be explained, is coordinated with the switching device 7. At the same time the signals amplified by the line amplifier 5 are caused to actuate the magnetic recorder unit 11 and to produce a non-pictorial record of the received signals upon a magnetic tape element 19. The tape element 19 is driven over a pair of rollers 21 and 23 which, in turn, are driven from the same prime mover 17 which drives the facsimile recorder 15. Such drive may be in any conventional form, of which the belt drive 25 is illustrated by way of example. Spaced from the magnetic recorder unit 11, whose output appears at the points 26 and 27, is a magnetic pick-up unit 29 which translates at the points 30 and 31 the signals recorded upon the tape 19 to convert these signals to electrical energy and then supplies the resultant electrical signals to the amplifier 33. The points 26 and 27, on the one hand, and 30 and 31, on the other hand, are spaced apart a distance such that in one preferred form of the arrangement the magnetic tape 19 moves in the direction of the arrow exactly the distance between the points 26 and 27 and the points 30 and 31 during the time that one line of the picture is being recorded by the facsimile recorder 15, and a suitable speed control is established between the motor 17 and the driven elements to achieve the result. The switch control unit 9 is one which is controlled by the available incoming signal, as supplied from the line amplifier and converter 5, in such manner that whenever any drop-outs or fill-ins occur the facsimile recorder is switched to the output of the amplifier 33 for recording purposes instead of to the output of the line amplifier and converter unit 5.

In the particular improvement in which the invention has been illustrated the switching device 7 and the switch control unit 9 have been shown in further detail. Under normal conditions the incoming signals as passed from the line amplifier and converter unit 5 are passed through

the transformer 35 to an amplifier tube 37 and there amplified still further, and the output of this amplifier is then coupled through a transformer and a line 40, 41 to actuate the facsimile recorder 15. Simultaneously the output signal from the line amplifier and converter 5 is supplied to a rectifier and filter unit 43 of any conventional design which is a part of the switch control unit 9. The time constant of this filter is preferably long enough to hold the output voltage produced across the load resistors 45 and 47 reasonably free from fluctuation due to the dot or impulse frequency of the picture signals. The polarity and characteristics of the rectifier and filter load resistors 45 and 47 are such that the tube 49 is normally in a state of conduction and the tube 51 is operating near the cut-off point. Under this condition the current flowing through the load resistor 53 is such that the tube 37 is biased for normal amplifying action and current through the resistor 55 is so low that the battery 57 is sufficient to bias the tube 59 to a cut-off. However, whenever the incoming signal fails or drops below a predetermined amplitude level due to fading, for example, the voltage developed across the resistors 45 and 47 will become so low that the effective or total bias upon the tube 51 will permit it to increase conduction and take control over the tube 49. This general type of tripping or flipping circuit has already been disclosed in the patent to J. L. Finch No. 1,844,950. Under this condition the current flowing through load resistor 53 will drop to a relatively small value and amplifier tube 37 will become inoperative due to being blocked out due to applied bias from the source 58. However, the amplifier tube 59 will now become operative due to the voltage developed across the resistor 55, which shifts the bias of the tube 59 to a normal value. During the interval of time when the tube 59 is operated the signals from the amplifier 33 will be passed on to the recorder 15 instead of the regular or direct signals from the line amplifier 5. Hence the signals obtained from the magnetic tape 19 by way of the magnetic pick-up unit 29 picking the signals up from the tape at the points 30 and 31 to convert them back into electrical energy so that it may be recorded, as hereinabove explained. As soon as the incoming signal in the receiver amplifier 3, for instance, returns to a normal amplitude it is obvious from what is herein explained that the tube 49 of the switch control unit will again regain control and the recording of the message by the recorder unit 15 will continue in the normal manner. It should be understood that the driving motor 17 which is controlled by the received synchronizing and framing signals hereinabove explained is so arranged as to drive both the facsimile recorder and the magnetic tape.

The signals recorded upon the magnetic tape 19 by means of the magnetic recorder 11 to form the non-pictorial record are then wiped or erased from the tape by the magnetic eraser unit 61 between the points 63 and 64 of which the tape passes. This unit is of standard form and is so well known that further and complete illustration is considered to be unnecessary. After the magnetic record is removed from the tape 19 the tape is used again to record signals as before explained.

Many modifications of the system hereinabove suggested will, of course, become apparent and at once suggest themselves to those skilled in the art and, therefore, I believe myself to be entitled to make and use any and all these modifications

which fall within the scope of the hereinafter appended claims.

Having now described my invention, I claim:

1. A picture reproducing apparatus comprising means to receive picture signals, means to produce a pictorial record of the received signals and means to produce a non-pictorial record of the received signals, and means for converting the non-pictorial record into a pictorial record at time periods when the signal strength received falls below a predetermined average value necessary to produce the pictorial record.

2. A picture reproducing apparatus comprising means to receive picture signals, means to produce a pictorial record of the received signals, means to simultaneously produce a non-pictorial record of the received signals, means for converting the non-pictorial record into a pictorial record of received signals, and means for limiting the conversion of the non-pictorial record into a pictorial record to time periods when the average received signal strength is less than a predetermined value.

3. A picture reproducing apparatus comprising means to receive picture signals, means to produce both a pictorial record and a non-pictorial record of the received signals, means to convert the non-pictorial record into electrical signal energy subsequent to its production, and switching means operative in accordance with a departure in incoming signal energy level from a predetermined average level to select between the two forms of signal energy to control the recording so that the pictorial record is produced at time periods when the signal strength received instantaneously falls below the predetermined average value under the control of the previously recorded signal energy.

4. A picture reproducing apparatus comprising means to receive picture signals, means to produce a pictorial record of the received signals, means to simultaneously produce a non-pictorial record of the received signals, means for converting the non-pictorial record into a pictorial record of received signals, and switching means for limiting the useful conversion of the non-pictorial image into a pictorial record to time periods when the average received signal strength is less than a predetermined value.

5. In a picture receiving apparatus, means for amplifying the received signals, means for recording a pictorial record of the received signals under the control of the signals received, means for producing a magnetic record of all of the received signals, means for converting the magnetic record of the received signals into electrical energy with a predetermined time delay subsequent to the production of the magnetic record, and means for switching the control of the pictorial reproduction of the received signals to the electrical energy developed by conversion of the magnetic record at time periods when the average signal strength is below a predetermined value so that there is recorded a continuous pictorial record of signals.

6. In a picture receiving apparatus, means for receiving picture signals, means for recording a pictorial record of the received signals, means for producing a magnetic record of all of the received signals simultaneously with the pictorial recording thereof, means for converting the magnetic record of the received signals into electrical energy a predetermined time subsequent to the production of the magnetic record, means for switching the control of the pictorial reproduc-

tion of the received signals to the electrical energy developed by conversion of the magnetic record at time periods when the average signal strength is below a predetermined value so that there is recorded a continuous pictorial record of signals, and integrating means to control the time period within which said switching means is operative.

7. A picture reproducing apparatus comprising means for receiving image and synchronizing signals, picture reproducing apparatus for converting received signal energy into a pictorial record, switching means interposed between the picture-reproducing means and the receiving means, means for producing a non-pictorial record of all received signals, means for converting the non-pictorial record into electrical energy with a predetermined time delay after the production of the non-pictorial record, switch control means operative in accordance with the average strength of received signals for controlling the activation of the pictorial reproducer by one of the directly received signals and the signals resulting from conversion of the non-pictorial record into electrical energy, and means for coordinating the rate at which each of the pictorial and non-pictorial records are produced.

8. A picture reproducing apparatus comprising means for receiving signals representing a pictorial image, reproducing apparatus for converting the received signal energy into a pictorial record, switch means interposed between the reproducing apparatus and the receiving means, means for producing a non-pictorial record of all received signals, means for converting the non-pictorial record into electrical energy a predetermined time subsequent to the production of the non-pictorial record, switch control means operative in accordance with the average strength of received signals for switching the control of the reproducing apparatus between the directly received signals and the signals resulting from conversion of the non-pictorial record into electrical energy, and means for normally excluding the non-pictorial record element from the control of the pictorial reproductions.

9. A picture reproducing apparatus comprising means for receiving image signals representing a picture subject, picture reproducing apparatus for converting received signal energy into a pictorial record, switching means interposed between the picture reproducing apparatus and the receiving means, means for producing a non-pictorial record of all received signals, means for converting the non-pictorial record into electrical energy a predetermined time subsequent to the production of the non-pictorial record, switch control means operative in accordance with the average strength of received signals for controlling the activation of the picture reproducing apparatus by one of the directly received signals and the signals resulting from conversion of the non-pictorial record into electrical energy.

10. Picture reproducing apparatus comprising signal receiving means for receiving signals representative of a pictorial record, means for converting said signals into a pictorial record, means for simultaneously converting said signals into a non-pictorial record, means for converting the non-pictorial record into electrical signal energy subsequent to the production of the non-pictorial record, means for intermingling the signals resulting from the conversion of the non-pictorial record into electrical signal energy with the initially received signals to produce the pictorial record, and means for excluding the electrical signal

energy developed from the non-pictorial record from the control of the picture reproduction during all time periods when the initially received signal energy is above a predetermined average value.

11. In picture receiving apparatus receiving means for receiving signals from which a pictorial representation is to be produced, means for recording the signals received as a pictorial record, means for simultaneously recording the signals received as a non-pictorial electro-magnetic record, means for converting the non-pictorial electro-magnetic record of the received signals into electrical energy at predetermined times sub-

sequent to the initial production of the non-pictorial record, means for switching the control of the pictorial signal reproduction between the initially received signal energy and the electrical energy developed from the conversion of the non-pictorial electro-magnetic record, and means for limiting the useful switching period of the pictorial reproduction by the electrical energy developed from the non-pictorial electro-magnetic record to time periods when the average strength of the received signal energy is less than a predetermined average intensity.

WARREN H. BLISS.
